(57) **CLAIM**

The ornamental design for a deposition ring for a substrate processing chamber, as shown and described.

DESCRIPTION

FIG. 1 is an enlarged top isometric view of a deposition ring for a substrate processing chamber, according to the first embodiment of the novel design.

FIG. 2 is a top plan view thereof.

FIG. 3 is a bottom plan view thereof.

FIG. 4 is a left elevation view thereof.

FIG. 5 is a right elevation view thereof.

FIG. 6 is a front elevation view thereof.

FIG. 7 is a rear elevation view thereof.

FIG. 8 is a cross-sectional view taken along line 8-8 of FIG. 2.

FIG. 9 is an enlarged top isometric view of a deposition ring for a substrate processing chamber, according to the second embodiment of the novel design.

FIG. 10 is a top plan view thereof.

FIG. 11 is a bottom plan view thereof.

FIG. 12 is a left elevation view thereof.

FIG. 13 is a right elevation view thereof.

FIG. 14 is a front elevation view thereof.

FIG. 15 is a rear elevation view thereof; and,

FIG. 16 is a cross-sectional view taken along line 16-16 of FIG. 10.

The dashed lines in FIGS. 1-8 represent unclaimed environment forming no part of the claimed design.
